UNITED STATES PATENT OFFICE.

HARVEY L. HOPKINS, OF CHICAGO, ILLINOIS, ASSIGNOR OF ONE-HALF TO ARLOA B. GLADE, OF CHICAGO, ILLINOIS.

MOWING-MACHINE.

1,121,836.

Specification of Letters Patent. Patented Dec. 22, 1914.

Application filed November 20, 1913. Serial No. 802,089.

To all whom it may concern:

Be it known that I, HARVEY L. HOPKINS, a citizen of the United States, and a resident of Chicago, in the county of Cook and State 5 of Illinois, have invented certain new and useful Improvements in Mowing-Machines, of which the following is a full, clear, and exact specification.

My invention is concerned with mowing 10 machines, and is designed especially to produce a machine having so light and perfectly balanced a draft that a longer cutter-bar than is customarily employed may be used with the machine, and still leave the 15 draft light enough so that a single team can readily pull the machine through any cutting that may be met with in actual practice.

To this end, I have devised certain novel 20 connections between the frame, the finger-bar, and doubletrees, so that any desired portion of the weight of the cutting apparatus may be transferred to the driving wheels, thereby increasing the traction of 25 said wheels and decreasing the pressure or weight of the cutting apparatus on the ground, thus reducing the draft.

To illustrate my invention, I annex hereto 30 four sheets of drawings, in which the same reference characters are used to designate identical parts in all the figures, of which,—

Figure 1 is a top plan view of the right-hand side of the machine, with the cutter-bar broken off and the tongue partially 35 broken out to show the connections beneath it; Fig. 2 is a rear elevation of so much of the machine as is seen in Fig. 1; Fig. 3 is a side elevation of the machine as seen with the right-hand wheel removed; Fig. 4 is a 40 vertical section as seen on the line A—A of Fig. 1; and Fig. 5 is a detail as seen on the line B—B of Fig. 1, looking in the direction of the arrows associated with said section line.

The main frame of the machine is journaled on the axle 10, which has supporting 45 wheels 11 and 12 journaled thereon, with the customary ratchet connections which compel the shaft to rotate with the wheels 50 as the machine is drawn forward, but which permit of the wheels turning backward on the shaft, as is necessary in backing and turning corners. The main frame has bearing sleeves 13, 14 and 15 for the shaft 10, 55 and between the sleeves 14 and 15 rise sup-

porting ears 16 and 17, between which is pivoted by a bolt 18 a bracket 19 in which the tongue 20 is secured. The seat 21 is secured on a spring bar 22, which is secured at its lower end to the tongue by a bolt 23. 60

When the weight of the driver is sufficient, the bar 22 is flexed to come in contact with a lug 24 projecting upward from the bracket 19. To utilize the weight of the driver in overcoming the upward thrust of the gearing 65 on the main frame, I provide a sleeve 25 projecting downward from the bracket 19 and containing a helically-coiled expanding spring 26, the lower end of which engages a plunger 27, the lower end of which engages 70 a bearing surface 28 projecting from the rear of the main frame so that the weight of the driver is yieldingly transmitted to the rear of the main frame and tends to overcome the upward thrust of the gearing. 75

The wheel 12 has secured thereon the spur-gear-wheel 29, which meshes with the customary spur-gear-pinion (not shown) secured on the end of a countershaft 30 which is journaled in bearing sleeves 31 and 32 80 forming a part of the main frame. The

customary clutch mechanism, inclosed in the cylindrical portion 33 of the gear casing 34 pivoted to the main frame at 35, is operated 85

by the clutch-shifting lever 36 in the customary manner to throw the countershaft 30 into and out of engagement with the customary bevel-gear wheel 37, which meshes with the customary bevel pinion 38 secured on the end of the customary pitman-shaft 39, which 90

is journaled in a bearing sleeve 40 projecting downward and forward from the main frame and supported by webs 41 and 42 extending from said sleeve back to the bearing sleeves for the main shaft 10. This pitman-shaft 39 carries the customary crank-head 95 43 having the crank-pin 44 on which one end of the pitman 45 is mounted, the other end of which is connected by the customary ball-and-socket joint 46 with the cutter-bar 47, which reciprocates in the customary finger-bar 48 in the customary manner.

The bearing sleeve 40 has formed thereon a bracket 49, which has secured in the upper end thereof a pin 50 which extends into the 100 segmental slot 51 formed in the bracket 52, which is pivoted at 53 to the aforesaid bracket 49. The bracket 52 has a pair of ears 54 and 55, between which is pivoted, by a bolt 56, a cylindrical bearing-sleeve 57, 110

The bearing sleeve 40 has formed thereon a bracket 49, which has secured in the upper end thereof a pin 50 which extends into the 105 segmental slot 51 formed in the bracket 52, which is pivoted at 53 to the aforesaid bracket 49. The bracket 52 has a pair of ears 54 and 55, between which is pivoted, by a bolt 56, a cylindrical bearing-sleeve 57,

which is pivotally connected by a bolt 58 with a yoke 59 formed on the upper end of the finger-bar supporting arm 60.

The connections just described between the bracket 49 and the finger-bar supporting arm produce a universal joint which permits the finger-bar-supporting arm to swing in a vertical plane on the pivot 58 and in a horizontal plane on the bolt 56, while the finger-bar-supporting arm can be tilted as a whole to vary the angle of the shoe 61 secured on its lower end relative to the ground over which the machine is traveling.

Projecting to the right from the forward portion of the body of the bracket 19 is a foot-rest 62 which has a bearing stud 63 formed on its outer end, and mounted on this bearing stud is a hand lever 64 which is normally held by a helically-coiled expanding spring 65 secured between the hub of said hand lever and the washer 66 in engagement with one of three notches 67 formed in the periphery of a sheave 68 journaled on the bearing stud 63. A dog 69 pivoted on a lug 70 projecting up from the foot-rest 62 engages detent teeth (not shown herein, but disclosed in my aforesaid prior Patent No. 307,948) on the adjacent side of the sheave 68 and holds said sheave in any position to which it may be advanced by the lifting lever 64 until the dog 69 is tripped by pressing the foot on the foot-rest 62 against the tail 71 of said dog. A chain 72 is secured at one end to the periphery of the sheave 68, and its other end is connected to an ear 73 projecting upward from the finger-bar-supporting arm 60, so that by swinging the lever 64, the chain 72 can be wound up on the sheave 68. As it is necessary to swing said sheave through 270° or more to raise the finger-bar 48 to the height that is desired when the machine is being transported from one place to another, or in passing through gates, the arrangement shown by which the lifting lever 64 can be swung several times through an arc of 90° to rotate the sheave 68 through several times as many degrees is employed.

The general construction thus far described is shown, except in the specific details of the pivotal connections between the sleeve 40 and the finger-bar supporting arm 60, in my prior Patent No. 307,948, and I will now proceed to describe the novel connections with which my present invention is concerned.

Suspended from the tongue 20 by a chain 74 attached to the pin of a clevis 75 is the doubletree 76 carrying the customary swingletrees 77 to which the team is hitched. The clevis 75 is formed integral with or rigidly secured to the draft-bar 78, which is preferably bent as shown, and is secured by the pin 79 of the clevis 80 to a short link 81, the other end of which is pivoted on a

pin 82 mounted in suitable bearings on the top of the cutter-bar supporting arm 60. This pin 82 is substantially in horizontal alinement with the pin 53 on which the cutter-bar supporting finger is ultimately pivoted, so that the draft applied to this pin does not tend to tilt the cutter-bar. Attached to the clevis 80 is a chain 83 extending rearward to and connected by the clevis 84 with a downwardly projecting arm 85 formed integral with or rigidly secured to the under side of the main frame. A helically-coiled contractile spring 89 has one end connected to the clevis 80, while its other end is secured in the desired one of the notches 90 formed in the outer end of a lever 91 which is pivoted at 92 to a bracket 93 extending rearwardly from the main frame and terminating at a point in alinement with, but considerably below, the countershaft 30. This lever 91 has pivoted thereon a link 94, which is pivoted at 95 to a lever 96 of the third class, which lever has its fulcrum formed by the short rock shaft 86, to which shaft said lever is pinned, and which is journaled in the bearings 87 and 88 projecting downward from the main frame directly beneath the bearing 15. The lever 96 curves downwardly and outwardly, and its widened and concaved end 97 engages the under side of a thrust bar 98 toward its forward end. This thrust bar 98 has its rear end connected by a ball-and-socket joint with a bearing bracket 99 secured on the main frame at the right-hand end thereof and directly beneath the axle 10. The forward end of this thrust bar 98 is pivoted between the ears 100 formed on the shoe 61 near the point where said shoe merges into the cutter-bar supporting arm 60. The chain 83 normally hangs loose, as seen in Fig. 3, but as soon as the draft is applied, the bar 78 is drawn forward to the dotted-line position, rocking over the link 81 to an extent that varies with the resistance to the movement of the machine. Ordinarily the chain 83 does not have all the slack taken up, in which case the tension of the draft applied to the bar 78 is transmitted through the spring 89 to the lever 91, which, through the link 94 acting on the lever 96, tends to raise the forward end of said lever, which forward end acting on the thrust bar 98 tends to raise the shoe 61 sufficiently so that it slides over the ground freely and offers little resistance. The cutter bar 48 being rigidly secured to the shoe 61, is also affected by this raising action, and is also drawn over the ground with little resistance or friction thereon.

The clevis 75 has connected thereto a helically-coiled contractile spring 101, which is connected at its inner end to a link 102, which link is connected at its inner end to the ear 73, to which the chain 72 is con-

nected, and these connections between the shoe and the doubletree also serve to yieldingly lift the shoe 61 and assist in securing the desired freedom of movement over the ground. As I have heretofore stated, under ordinary conditions of draft the chain 83 is not drawn taut, but in case of extreme resistance the spring 89 is stretched sufficiently so that the chain 83 is drawn taut, in which case all the surplus draft is applied directly to the arm 85, which, being rigid with the main frame, tends to rotate the latter on the axle 10 in direct opposition to the tendency of the gearing (increased in difficult cutting) to thrust down the forward end of the main frame, and thus increase the friction of the cutter-bar and attached shoe on the ground.

In raising the outer end of the cutter-bar so as to swing it far enough toward a vertical position to pass through gates, it is necessary to confine the upward movement caused by the lifting action of the chain 72 to the shoe 60 and the attached cutter-bar 48, instead of lifting the frame, and for this purpose, I form on the main frame an upwardly extending stud 103, and opposed to the same is a stud 104 extending downwardly from the under side of the bracket 19. Ordinarily, in the use of the lifting lever 64 to clear small obstructions, the main frame, together with the inner end of the cutter-bar, is lifted until the lug 103 contacts with the lug 104 and prevents the further upward movement of the main frame, after which the upward movement is necessarily confined to the finger-bar 38 and its supporting arm 60. To prevent even this limited amount of upward movement of the main frame when it is desired to raise the outer end of the cutter-bar only, I provide a foot lever 105, which is pivoted to the bracket 19 at 106, and has an arm 107 on its upper end projecting in position to be engaged by the left-hand foot of the driver when it is placed on the foot-rest 108, which is formed on the opposite side of the bracket 19 from the foot-rest 62. The lever 107 has formed on and projecting inwardly from its lower end a wedge-shaped piece 109, which can be swung into the dotted-line position shown in Fig. 4, where it is interposed between the ends of the lugs 103 and 104 and prevents the upward movement of the main frame preliminary to the upward movement of the outer end of the cutter-bar and its supporting arm 60.

The connections heretofore shown are so arranged that the shoe 61 rides over the ground without its angle relative to the ground being interfered with by their movement or manipulation. To tilt it to vary the height of the cut, I employ a tilting lever 110, which is pivoted at 111 to a bracket 112 extending downwardly from the tubular

bearing 40. This lever is provided with the customary detent 113 and the handle 114 connected thereto by the link 115, so that by raising the detent 113, the lever can be swung over the notched segment 116 and 70 engaged in any desired position of adjustment. This lever is connected by a link 118 with an arm 119 projecting upward from the casting 52, so that said casting can be swung to tilt the shoe 61 and the attached 75 cutter bar 48 to any desired extent.

While I have shown and described my invention as embodied in the form which I at present consider best adapted to carry out its purposes, it will be understood that it is 80 capable of modifications, and that I do not desire to be limited in the interpretation of the following claims except as may be necessitated by the state of the prior art.

What I claim as new, and desire to secure 85 by Letters Patent of the United States, is:

1. In a mowing machine, the combination with a frame and supporting wheels therefor, of a finger bar having a shoe on its inner end, pivotal connections between the shoe and the frame, a thrust bar connecting the frame and shoe, a lever fulcrumed on the frame and engaging the under side of the thrust bar, a tongue carried by the main frame, doubletrees, and means connecting 95 the doubletrees and said lever whereby a portion of the draft tends to swing the lever to swing the thrust bar to lift the shoe.

2. In a mowing machine, the combination with a frame and supporting wheels therefor, of a finger bar having a shoe on its inner end, pivotal connections between the shoe and the frame, a thrust bar connecting the frame and shoe, a lever fulcrumed on the frame and engaging the under side of 100 the thrust bar, a tongue carried by the main frame, doubletrees, and means connecting the doubletrees and said lever whereby a portion of the draft tends to swing the lever to swing the thrust bar to lift the shoe, said 105 means including a draft rod connected at one end to the doubletrees, a second lever fulcrumed on the frame, means connecting the draft rod and the second lever, and means connecting the two levers whereby 110 the power applied to the second-mentioned lever is transmitted to the first-mentioned lever.

3. In a mowing machine, the combination with a frame and supporting wheels therefor, of a finger bar having a shoe on its inner end, pivotal connections between the shoe and the frame, a thrust bar connecting the frame and shoe, a lever fulcrumed on the frame and engaging the under side of 115 the thrust bar, a tongue carried by the main frame, doubletrees, and means connecting the doubletrees and said lever whereby a portion of the draft tends to swing the lever to swing the thrust bar to lift the shoe, said 120

means including a draft rod connected at one end to the doubletrees, a second lever fulcrumed on the frame, means connecting the draft rod and the second lever, and a link connecting the two levers.

4. In a mowing machine, the combination with a frame and supporting wheels therefor, of a finger bar having a shoe on its inner end, pivotal connections between the 10 shoe and the frame, a thrust bar connecting the frame and shoe, a lever fulcrumed on the frame and engaging the under side of the thrust bar, a tongue carried by the main frame, doubletrees, and means connecting 15 the doubletrees and said lever whereby a portion of the draft tends to swing the lever to swing the thrust bar to lift the shoe, said means comprising a draft rod connected at one end to the doubletrees, a second lever 20 pivoted on the frame, a helically coiled contractile spring connecting the draft rod and the second lever, and connections between the two levers.

5. In a mowing machine, the combination 25 with a frame and supporting wheels therefor, of a finger-bar having a shoe on its inner end, pivotal connections between the shoe and the frame, a thrust bar connecting the frame and shoe, a lever fulcrumed on the frame and engaging the under side of the thrust bar, a tongue carried by the main frame, doubletrees, means connecting the doubletrees and said lever whereby a portion of the draft tends to swing 30 the lever to swing the thrust bar to lift the shoe, a draft rod connected at one end to the doubletrees, and a normally slack chain connecting the draft rod and the lever so that the pull of the chain tends to lift the forward 35 end of the frame.

6. In a mowing machine, the combination 40 with a frame and supporting wheels therefor, of a finger bar having a shoe on its inner end, pivotal connections between the 45 shoe and the frame, a thrust bar connecting the frame and shoe, a lever fulcrumed on the frame and engaging the under side of the thrust bar, a tongue carried by the main frame, doubletrees, and means connecting 50 the doubletrees and said lever whereby a portion of the draft tends to swing the lever to swing the thrust bar to lift the shoe, said means including a draft rod connected at one end to the doubletrees, a normally 55 slack chain connecting the other end of the draft rod and the lever so that the pull of the chain tends to raise the forward end of the frame, a helically-coiled contractile spring connecting the same end of the draft 60 rod with a second lever fulcrumed on the main frame, said second lever, and means connecting the first lever and the second lever whereby a portion of the draft applied to the draft-rod acts through the spring 65 and the two levers to lift the thrust bar

until the slack of the chain is taken up, after which the action is supplemented by said chain acting on the first named lever.

7. In a mowing machine, the combination with a frame and supporting wheels therefor, of a finger-bar supporting arm pivoted thereon, a tongue supported by the frame, doubletrees suspended from the tongue, and draft means connecting the doubletrees, finger-bar supporting arm and frame, said 70 means including a draft rod connected at one end to the doubletrees, a link pivoted on the finger-bar supporting arm to which the other end of the draft rod is connected, a lever fulcrumed on the main frame, a thrust 75 bar connecting the main frame and the finger-bar supporting arm, a second lever fulcrumed in the main frame and having its load end engaging the under side of the thrust bar, means connecting the levers 80 whereby the power applied to the first is transmitted to the second, and means connecting the draft-rod and power-arm of the first-mentioned lever whereby the pull on the draft-rod in part serves to lift the thrust 85 bar.

8. In a mowing machine, the combination with a frame and supporting wheels therefor, of a finger-bar-supporting arm pivoted thereon, a tongue supported by the frame, doubletrees suspended from the tongue, and draft means connecting the doubletrees, finger-bar-supporting arm and frame, said 90 means including a draft-rod connected at one end to the doubletrees, a link pivoted on the finger-bar-supporting arm to which the other end of the draft-rod is connected, a lever fulcrumed on the main frame, a thrust bar connecting the main frame and the finger-bar-supporting arm, a second lever fulcrumed in the main frame and having its load end engaging the under side of the thrust bar, a link connecting the two levers whereby the power applied to the first is 100 transmitted to the second, and means connecting the draft-rod and power-arm of the first-mentioned lever whereby the pull on the draft-rod in part serves to lift the thrust 105 bar.

9. In a mowing machine, the combination with a frame and supporting wheels therefor, of a finger-bar-supporting arm pivoted thereon, a tongue supported by the frame, doubletrees suspended from the tongue, and draft means connecting the doubletrees, finger-bar-supporting arm and frame, said 110 means including a draft-rod connected at one end to the doubletrees, a link pivoted on the finger-bar-supporting arm to which the other end of the draft-rod is connected, a lever fulcrumed on the main frame, a thrust bar connecting the main frame and the finger-bar-supporting arm, a second lever fulcrumed in the main frame and having its load end engaging the under side of the 115

- thrust bar, means connecting the levers whereby the power applied to the first is transmitted to the second, and a helically-coiled contractile spring connecting the link and the power-arm of the first-mentioned lever whereby the pull on the draft-rod in part serves to lift the thrust bar.
10. In a mowing machine, the combination with a frame and supporting wheels therefor, of a finger-bar-supporting arm pivoted thereon, a tongue supported by the frame, doubletrees suspended from the tongue, and draft means connecting the doubletrees, finger-bar-supporting arm and frame, said means including a draft-rod connected at one end to the doubletrees, a link pivoted on the finger-bar-supporting arm to which the other end of the draft-rod is connected, a thrust bar connecting the frame and finger-bar-supporting arm, a lever fulcrumed on the main frame and having its load end engaging the under side of the thrust bar, and means connecting the link and the lever whereby the pull of the draft-rod in part serves to lift the thrust bar.
11. In a mowing machine, the combination with a frame and supporting wheels therefor, of a finger-bar-supporting arm pivoted thereon, a tongue supported by the frame, doubletrees suspended from the tongue, and draft means connecting the doubletrees, finger-bar supporting arm and frame, said means including a draft-rod connected at one end to the doubletrees, a link pivoted on the finger-bar supporting arm to which the other end of the draft-rod is connected, a thrust bar connecting the frame and finger-bar supporting arm, a lever fulcrumed on the main frame and having its load end engaging the under side of the thrust bar, and a chain connecting the link and the frame whereby the pull of the draft-rod in part serves to lift the forward end of the frame.
12. In a mowing machine, the combination with a frame and supporting wheels therefor, of a tongue pivoted on the frame, a finger-bar pivotally mounted on the frame, a lifting lever mounted on the tongue, means connecting the lifting lever and the finger-bar whereby by swinging the lever the finger-bar may be raised, engag-
- ing surfaces on the tongue and frame to limit the amount that the latter may be raised relative to the tongue, and means for diminishing this amount.
13. In a mowing machine, the combination with a frame and supporting wheels therefor, of a tongue pivoted on the frame, a finger-bar pivotally mounted on the frame, a lifting lever mounted on the tongue, means connecting the lifting lever and the finger-bar whereby by swinging the lever the finger-bar may be raised, engaging surfaces on the tongue and frame to limit the amount that the latter may be raised relative to the tongue, and means for diminishing this amount, consisting of a lever having a separating member adapted to be swung when desired between said engaging surfaces.
14. In a mowing machine, the combination with a frame and supporting wheels therefor, of a finger-bar, pivotal connections between the finger-bar and frame, a doubletree, and draft means connecting the doubletree, finger-bar and frame, tending to lift the finger-bar and the forward end of the frame, said means including a spring through which the draft is applied to lift the finger-bar without lifting the frame until said spring has yielded to a certain limit, after which the draft is also applied to the frame to lift it.
15. In a mowing machine, the combination with a frame and supporting wheels therefor, of a finger-bar, pivotal connections between the finger-bar and frame, a doubletree, and draft means connecting the doubletree, finger-bar and frame, tending to lift the finger-bar and the forward end of the frame, said means including a spring through which the draft is applied to lift the finger-bar without lifting the frame, and a normally slack chain connected to the frame to lift it when the spring has been distended sufficiently to take up the slack.

In witness whereof, I have hereunto set my hand and affixed my seal, this eighth day of November, A. D. 1913.

HARVEY L. HOPKINS. [L. S.]
